UNITED STATES PATENT OFFICE

CHARLES DAWSON, OF TACOMA, WASHINGTON.

WHEAT SCOURING, WASHING, AND DRYING MACHINE.

1,116,572.

Specification of Letters Patent. Patented Nov. 10, 1914.

Application filed February 26, 1914. Serial No. 821,343.

To all whom it may concern:

Be it known that I, CHARLES DAWSON, a citizen of the United States, and a resident of Tacoma, in the county of Pierce and State 5 of Washington, have invented certain new and useful Improvements in Wheat Scouring, Washing, and Drying Machines, of which the following is a specification.

This invention relates to machines for 10 cleaning wheat and especially to such as wash and dry the wheat to separate it from the smut and other impurities therein.

The objects of my invention are to improve the machines at present in use for this 15 purpose whereby the wheat will be more thoroughly scoured, washed, and dried; whereby a more perfect ventilation is secured throughout the chambers; and whereby the efficiency of the machines is materially 20 improved. I attain these and other objects by the devices, mechanisms and arrangements illustrated in the accompanying drawings, in which—

Figure 1 is a side elevation, partly in 25 section, showing my improved machine; Fig. 2 is an end elevation thereof; Fig. 3 is a cross-section thereof; Fig. 4 is a side elevation of a small portion of the lower drum showing a part of the covering plate in the 30 scouring section of the drum; and Fig. 5 is a section along the edge of one of the ventilating end plates of the drums.

Similar numerals of reference refer to similar parts throughout the several views.

35 The wheat is fed into the distributing box 1 through the pipe 2, from whence it flows into the conditioner 3, in the usual manner. A stream of water passes from the pipe 4 through the distributing box 5 into the same 40 conditioner at a point immediately below the stream of wheat, and the two streams mix and flow over the riffles 6 which collect any foreign substances mixed with the wheat (such as stones, nails, etc.) The 45 mixed stream then flows down the inclined chute 7 into the lower part of the scouring section of the washer.

The washer consists of two horizontal cylindrical drums mounted one over the 50 other in a suitable framework, in which suitable beaters revolve as hereinafter described, each drum being formed of perforated plates. The lower drum 8, into which the stream of water and grain is discharged, 55 is surrounded at its receiving end by an unperforated plate 9 outside of the perforated

plate, said plate 9 extending entirely around the drum and about one-fifth of its length from the said receiving end. If desired, the 60 perforated plate may be eliminated in that portion under the plate 9 and a surfacing of abrasive material, such as carborundum, may be applied to the interior surface of the 65 said plate 9. That portion of the cylinder 8 which is surrounded by the plate 9 is 70 where the wheat is thoroughly washed and scoured, either against the rough perforations in the plate or against the abrasive on the inside of the plate 9, but in either case the water does not escape from the cylinder 75 at this point. As before stated, the remainder of the cylinder 8 is formed with perforated walls, as is also the upper cylinder 10 which is similar to the cylinder 8 except that it has no portion inclosed by an unperforated plate. The frames in which the 80 cylinders 8 and 10 are mounted are provided with suitable bearings 11 coaxial with the said cylinders, and shafts 12 turn therein, being driven by suitable means. Air is admitted to the said cylinders through revolving 85 ventilators each secured to the shaft 12 at the required point and turning therewith. These ventilators consist of a number of radiating vanes 13 which overlap each other 90 and which are shaped substantially as shown in Fig. 5 so as to scoop up the air with their outer edges and force it inward into the cylinder with their inner edges, the overlap being such that the water and grain will not 95 escape through them while they are in motion. One of these ventilators is mounted at each end of the cylinders 8 and 10 and drives a supply of fresh air thereinto. Each shaft 12 is also provided with a series of beaters secured thereto by suitable radiating arms 14.

The beaters consists of plates 15 which are mainly spirally bent but which are not radial to the axis of the shaft but are inclined backward therefrom as shown in Fig. 100 3. The receiving end 16 of each beater plate is bent out of the spiral shape to scoop up the wet grain and carry it at once away from the end ventilator and feed it to the spiral part of the beater. The delivery 105 end 17 of each beater is also bent out of the spiral shape having its edges parallel with the axis of rotation and having a slight curve on the extreme end to keep the grain from the adjacent ventilator. The two cylinders 8 and 10 are connected together by 110 a suitable pipe 18, and a delivery pipe 19

is mounted at the delivery end of the upper cylinder 10. A vent hole 20 is provided in the upper side of said delivery pipe 19. The shafts are driven at equal speeds but 5 in opposite directions in the two cylinders 8 and 10.

My machine operates in the following manner: The grain issues from the conditioner in a very wet and dirty condition and 10 is received in the end of the lower cylinder 8; here it is engaged by the beaters as they are rotated, and is repeatedly thrown against the rough sides of the cylinder and is thus scoured clean; it gradually is drawn 15 away from the scouring portion by the spiral form of the beaters and then is similarly thrown against the perforated plates of the cylinder, through which the dirty water passes, being aided by the draft of air 20 forced in at each end of the cylinder by the rotating ventilators; in this way the grain gives up a large proportion of the water and it is finally thrown up the connecting passage 18 to the upper cylinder 10 where 25 it is again seized by the beaters therein and all the remaining moisture is driven out therefrom by the centrifugal action and by the draft of air which passes outward through the perforations, until the grain 30 reaches the end and is thrown out therefrom through the delivery pipe 19.

Having described my invention, what I claim is:

In a wheat washing and drying machine, the combination with a fixed frame; of a 35 hollow horizontal drum mounted thereon, said drum having no perforations therein at its receiving end but being perforated elsewhere; a rotating shaft mounted coaxially within said drum and extending from end 40 to end thereof; inward acting ventilators mounted on said shaft at each end of the drum and adapted to force air into the drum at the ends and to drive it through the perforations in the wall thereof and to prevent the egress of grain from the drum; beaters mounted on said shaft and positioned whereby their acting surfaces are inclined rearwardly to the radius of rotation thereof and having their main portions bent 45 spirally about said shaft; scoop portions formed on the receiving ends of said beaters; and throwing portions formed on the delivery ends of said beaters and adapted to give the grain thrown thereby a tangential motion therefrom without any axial motion.

CHARLES DAWSON.
